FRED HOTCHNER, OF LOS ANGELES, CALIFORNIA

SWITCH

Application filed November 21, 1930. Serial No. 497,165.

This invention relates to a switch in which the insulating character of an extremely thin layer of gaseous conductor is utilized for the purpose of breaking a circuit.

5 It is known that in a discharge tube containing an ionization conductor and a pair of opposing spaced electrodes between the near opposing surfaces of which the discharge is confined a certain minimum distance is required between the opposing surfaces in order that conduction may take place. For instance in helium gas at a pressure of two millimeters of mercury when the distance is reduced to one millimeter between 10 the surfaces conduction virtually ceases. According to commonly accepted ideas today this distance is that at which an electron leaving the cathode travels before it hits an atom of the contained gaseous medium. In 15 other words it would be that distance in which insufficient collisions occur to set up the ionization necessary for free conduction, and is considered to be in the order of the mean free path of the molecules of the contained gas. A certain very small current 20 may flow under conditions where there is no ionization, but for all practical purposes this current can be neglected.

Broadly the invention has for its object 25 the utilization of this phenomenon in a switch for making and breaking a circuit. More specifically it has for its object the production of a device in which the technical conditions necessary to insure a clean make 30 and break action are realized with a minimum of complicating factors and in an apparatus capable of quantity production with a high degree of uniformity in performance.

It is an object of this invention to disclose 35 and provide an ionization conductor switch that may be simple, efficient and easy to fabricate.

Another object of this invention is to disclose 40 and provide a construction which permits accurate adjustment by visual methods.

A still further object of this invention is to disclose 45 and provide a mounting for a switch of the type described by means of which the device may be operated by rotation.

A particular embodiment of the invention shown also provides certain useful features of construction hereinafter described.

While I set forth herein a theory of the 50 operation of the device it is to be understood that the invention is not to be limited thereby.

The invention is illustrated by the preferred embodiment shown in the accompanying drawing, but it is to be understood that 55 I do not intend to be limited to the particular details shown, since many changes and modifications may be made and the invention embodied in widely different forms without departing from the spirit and scope 60 thereof in its broader aspects. Hence I desire to cover all modifications and forms coming within the language and scope of 65 any one or more of the appended claims.

In the drawing: 70

Fig. 1 is an elevation of a switch made according to this invention.

Fig. 2 is a cross section through the axis 75 of the tube shown in Fig. 1.

Fig. 3 is a perspective view partly broken away, of the movable element of the switch shown in the preceding views.

Referring more particularly to the drawing, 1 indicates an envelope which is evacuated and provided with a body of gas preferably at a low pressure and capable of conveying current by ionization at low voltages. As is well known in the art, under certain conditions a very thin layer of ionization conductor may become an excellent insulator. 80 The exact figure for the thickness of this layer varies with different gases under different conditions but, as ordinarily understood, it is fairly close to the length of the mean free path of the molecules of the gas. Therefore, two electrodes are provided within the envelope 1, the electrode 3 being stationary and being provided with a lead-in conductor 4 which extends through a reentrant stem 5 and is soldered onto the ferrule 6 at the point 7, 85 thereby providing contact to elements outside of the envelope 1. The other electrode 8 is slidable upon the lead-in conductor 9 making contact with it at all times through the spring contact 31. The conductor 9 ex- 90 95 100

tends through the reentrant stem 10 and connects with the ferrule 11 at the point 12. The ferrules 6 and 11 have extended portions 13 and 14 overlapping each other with respect to the axis of rotation A—A around which the tube is disposed to be rotated on the spindles 15 and 16, the electrode 8 thereby being caused to move by gravity toward or away from the electrode 3. The boss 17 on the end of the lead-in conductor 9 serves to limit the movement of the electrode 8 in both directions parallel with the axis of the tube, by cooperating with the end 20 of the electrode 8 and the cross bar 21. The space 22 between the approaching faces 23 and 24 of the electrodes is sufficiently small that conduction cannot take place between the two electrodes upon the application of any voltage which the switch is intended to operate on. If the tube is charged with helium gas at two millimeters of mercury pressure this distance should be under one millimeter. The diameter of the electrodes should be fairly large as compared with this dimension to insure that virtually all lines of force between the two electrodes are straight. Thus a diameter of one inch at a spacing of one millimeter and at a pressure of two millimeters in helium provides a condition in which so few lines of force terminate on the wall of the tube or are distorted by external conditions that the insulating effect is unimpaired by secondary conditions thus set up. The distance which the electrodes may move apart when properly rotated is so selected that conduction may take place freely therebetween when the electrodes are separated. This distance should preferably be the distance between the cathode and the end of the Faraday dark space, which is visible to ordinary inspection. It will be found to vary considerably under different conditions and is usually from one half inch to an inch and a half.

Certain conditions must be observed in fabricating a device of this character in order to secure economical production and a uniform product. The glass tube must have an inside diameter only slightly greater than the outside diameter of the electrodes, that is, just sufficient to allow the electrodes to expand during the process of degasification without applying pressure to the glass tube. The electrodes should be as thoroly degasified as possible before assembling the device in order that they need not be raised to a very high temperature when completing the switch. Thus the danger of melting the glass envelope is reduced and further a closer fit may be observed if it is not necessary to allow extra space for the expansion of the electrode. The space between the electrodes and the glass tube must also never exceed that dimension which would allow a flash over to occur past the electrode. It is necessary to insure that the discharge be confined to

the surfaces 23 and 24, for if the discharge flashes back between the electrodes and the wall of the tube to the rear of the electrodes or lead in wires the tube will freely conduct at all times. In order to insure that the space between the electrode and the wall does not in itself act as a cathode care should be taken that no deposit of metal is formed on the glass during fabrication, as under such conditions the discharge sometimes becomes localized to the cavity in preference to the adjacent exposed surfaces. I have found that by activating a surface such as the opposing surfaces 23 and 24 while leaving other adjacent surfaces in their natural condition the danger of the discharge wandering to the undesired surfaces is greatly reduced. Thus an activating coating of any of the alkali metal oxides may be used. This dimension can be determined best by experiment as it is a complicated function.

In fabricating the device, the space 22 may be visually determined and adjusted manually by the simple device of heating one of the ends of the tube and pressing the reentrant stem in or out until the electrodes are the correct distance apart. The ferrules 6 and 7 are secured to the tube with ordinary basing cement.

The device is evacuated at the tubulation 30 in the usual manner. The electrodes may be de-gasified by high frequency induction or by bombardment and the tube may be charged with the necessary ionization conductor by the methods well known in the art.

By the term "ionization conductor" as used herein I have reference to any fluid capable of sustaining a glow discharge and conveying current by the process of ionization. Typical of such fluids are the rare gases at low pressures and the vapors of metals.

By the term "glow discharge" as used herein I have reference to all discharges which take place through a fluid upon the application of electric potential across a body thereof resulting in the flow of current by the ionization of the molecules or atoms of said fluid which is characterized by the fact that a thin layer of said fluid close to the cathode acts as an insulator when it is mechanically divided from the main column of fluid in the device. It is to be here noted that this definition of a glow discharge does not necessarily coincide with that definition commonly used in the literature to distinguish one particular type of discharge from arc, coronas, or transitory types of discharge, but may include or overlap such other types under certain conditions within the purview of this invention. Nor is this definition to be understood as conditioned upon the appearance of a visible glow, as the condition herein contemplated may exist without the emission of visible radiation.

By the term "parallelly disposed opposing

surfaces" as herein used or other terms of the like purport it is to be understood that I am not limiting my devices to electrodes having plane parallel surfaces but I intend to include in this term surfaces which are conformed to compensate for electric field conditions such as condenser plates that are rounded at the edges, and I also intend to include such surfaces as depart from parallelism by an amount not inimical to the realization of the phenomenon herein described and the functioning of the device.

The invention is not limited to the embodiment as shown but may be variously embodied in ionization conductor devices and is to be limited only by the prior art and the appended claims.

Having thus described my invention, what I claim is:

1. In a switch, a tube of insulating material hermetically sealed and provided with an atmosphere of gaseous ionization conductor, cylindrical electrodes in said tube, at least one of which is slidable through said tube but fitting the inside wall of said tube so close as to prevent the discharge passing therebetween, and means to limit the movement of said electrode in two directions whereby said electrode may approach the other electrode so closely that no conduction may take place therebetween upon the application of voltage to said electrodes by virtue of the insulating effect of a thin layer of the ionization conductor.

2. In a switch a tube of dielectric material, electrodes within said tube having parallel disposed opposing surfaces, a gaseous ionization conductor in said tube, and means to vary the distance between said electrodes so that said electrodes may be brought together so close without touching that the layer of gas between the said opposing surfaces is non-conducting or may be separated to a greater distance such that the layer of gas remaining therebetween is conducting.

3. The method of making and breaking a circuit which consists in varying the distance between two electrodes immersed in a gaseous ionization conductor between two limits without touching, the lesser of which distances is so selected that the layer of said conductor remaining between the opposing surfaces of said electrodes is non-conducting.

4. A switch comprising an envelope, a gaseous ionization conductor therein, a pair of electrodes therein, conducting means providing contact between said electrodes and the outside of said envelope, and means to vary the distance between said electrodes between two limits without said electrodes touching at any time to make direct contact, the lesser of said limits being of such low value that when the electrodes are so positioned and potential is applied thereto no material conduction takes place therebetween by virtue of the insulating

quality of the thin layer of ionization conductor remaining therebetween, and the greater of said limits being of such high value that when the electrodes are so positioned and sufficient potential is applied thereto to cause ionization in said conductor free conduction takes place through said switch by virtue of the ionization of the contained medium between said electrodes.

5. A switch comprising an envelope, a gaseous ionization conductor therein, a pair of electrodes therein having parallelly disposed and opposing emitting surfaces, conducting means providing contact between said electrodes and the outside of said envelope, and means to vary the distance between said electrodes between two limits without said electrodes touching at any time to make direct contact, the lesser of said limits being of such low value that when the electrodes are so positioned and potential is applied thereto no material conduction takes place therebetween by virtue of the insulating quality of the thin layer of ionization conductor remaining therebetween, and the greater of said limits being of such high value that when the electrodes are so positioned and sufficient potential is applied thereto to cause ionization in said conductor free conduction takes place through said switch by virtue of the ionization of the contained medium between said electrodes.

6. A switch comprising an envelope, a gaseous ionization conductor therein, a pair of electrodes therein having parallelly disposed and opposing emitting surfaces, conducting means providing contact between said electrodes and the outside of said envelope, means to confine the discharge to the medium between said surfaces, and means to vary the distance between said electrodes between two limits without said electrodes touching at any time to make direct contact, the lesser of said limits being of such low value that when the electrodes are so positioned and potential is applied thereto no material conduction takes place therebetween by virtue of the insulating quality of the thin layer of ionization conductor remaining therebetween, and the greater of said limits being of such high value that when the electrodes are so positioned and sufficient potential is applied thereto to cause ionization in said conductor free conduction takes place through said switch by virtue of the ionization of the contained medium between said electrodes.

Signed at Los Angeles, California, this 17 day of November, 1930.
